MOP DEVICE HAVING AN INTEGRAL FLEXIBLE SUPPORT AND MEANS FOR DETACHABLY COUPLING A SPONGE TO SAID SUPPORT

Johann F. Kohlwey, Velp, and Manfred Klafter, Utrecht, Netherlands, assignors to American Enka Corporation, Enka, N. C., a corporation of Delaware

Application April 2, 1956, Serial No. 575,634

Claims priority, application Netherlands April 20, 1955

2 Claims. (Cl. 15—119)

This invention relates to the cleaning arts and more particularly to an improved mop of the type in which a sponge is affixed to an articulated support in order that the sponge may be wrung out during use.

It is known to provide mops in which the scrubbing surface is a sponge which is supported by a metal support that is so articulated as to permit the sponge to be folded upon itself for wringing out. While these devices are satisfactory from some points of view, rendering the metal support rust proof is expensive and forming the metal material to the exact shape desired involves a fabrication task which must be done well to produce a satisfactory product and yet which costs more than is warranted by the economic value of the product.

In an effort to overcome the need for sponge supports of metal, it has been proposed to use an all plastic, flexible backing. The flexible backing is completely satisfactory from the point of view of resistance to rust and the elimination of expensive fabrication steps, but its very flexibility renders it unsuitable as a sponge support when the sponge is in the scrubbing rather than the wringing out position. In other words the sponge is not firmly enough held in the scrubbing position. Furthermore, the sponge is glued to the flexible backing which makes the replacement of the sponge a difficult and unpleasant operation.

It is proposed according to the present invention to provide a mop comprised of a sponge and fully integral backing therefor, the support being characterized by overall rigidity with local zones of articulation and yet being easy to manufacture and fully satisfactory in all phases of use.

Other objects and advantages of this invention will be apparent upon consideration of the following detailed description of an embodiment thereof in conjunction with the annexed drawings in which:

Figure 1 is a perspective view of a mop constructed in accordance with the teachings of the present invention, the handle being broken away for the convenience of illustration; and

Figure 2 is a view in section taken along the line of 2—2 of Figure 1.

Referring now in greater detail to the drawings, the mop consists essentially of five parts: a sponge 10; backing plates, 11 and 12 therefor; a support 13 and a handle 14. The sponge 10 is an ordinary cellulosic one of the type now used for mops. The present invention is concerned with the mop assembly and the sponge support rather than with the sponge itself.

The sponge 10 is provided with backing plates 11 and 12 of uniform thickness and which cover both ends of the sponge, leaving a small intermediate zone where the top of the sponge is not provided with the backing. (See the arrowhead at the end of reference numeral 15.) Each piece of backing plates 11 and 12 is provided with four integral, upstanding studs 16, the shape of which is apparent from Figure 2. The backing plates 11 and

2

12 and the studs 16 are made of a suitable elastic material. The studs 16 are hollow and are provided with radially enlarged ends at 17 so that they may be pushed through holes cut in the support 13 ultimately to assume the projected position shown in the drawings. Note that at eight places, the support 13 is provided with apertures at 18. These are generally frustro-conical in shape, apex end up. Thus, as each stud 16 is pushed through the respective aperture at 18, its end 17 is gradually compressed until it ultimately emerges from the apex end of the hole. Once free of the defining walls of the aperture at 18, the resilient end 17 expands again to a locking position. To remove the sponge, the ends 17 require to be squeezed and retracted back through the apertures at 18. It can now be seen that by the use of the studs 16, the sponge and its backing plates 11 and 12 can be firmly, but nevertheless detachably, connected to the mop support 13.

The mop backing 13 is one solid piece of flexible, resilient, polyamide, elastic material, prepared by injection molding. The apertures 18 already described are molded in the backing and, in addition to that, they are molded in two grooves 19 and 20 on opposite sides of a ferrule-like portion 21 for the reception of the mop handle 14. Note that the grooves 19 and 20 more or less register with the areas of the sponge where there is no backing plates 11 or 12. The support 13 being thinner at the areas of these grooves than elsewhere, the grooves become lines of articulation parallel to the handle whereby the exposed face of the sponge 10 underlying the backing plate 11 can be bent into face engagement with the corresponding face underlying the backing plate 12. The mop support 13 is so stiff that articulation is not possible except in the grooved areas and, further to enhance this stiffness, there are provided generally U-shaped ribs 22 on opposite sides of the central portion 21 in order to stiffen the backing at the points which are not to be lines of articulation and in order to prevent the mop from moving toward the handle opposite to the direction of the arrows in Figure 1.

It has been found that if a polyamide starting material is used in the manufacture of the support 13 the thickness of material at the bottom of the grooves should be about 2 mm. Attention is directed to the fact that the sponge 10 of the present invention is not bent in one point through 180°, but rather a portion underlying the groove 19 is bent 90° and a portion underlying the groove 20 is likewise bent 90°. In this way, the total bend to which any part of the sponge is subjected is somewhat reduced and its wearing qualities are enhanced.

Attention is directed to the fact that the support 13 is not of uniform thickness even in the areas overlying the backing plates 11 and 12. Notice that the backing is thicker in the vicinity of the apertures at 18 than it is in between them. It is also thicker near the outer ends of the supporting body than it is in the middle of the end portions. This is for improved rigidity of the support during mopping operations, while at the same time, permitting localized flexibility for wringing out.

What is claimed is:

1. A mop comprising a sponge, an integral support of elastic material, said support including integral end portions separated from a central handle supporting portion by grooves of reduced thickness, said end portions having apertures therein, backing plates at opposite ends of said sponge, flanged compressible studs projecting from said backing plates and through the apertures in said end portions of said support to hold the sponge in position, said grooves providing lines of articulation for squeezing the supported sponge and reinforcing zones of increased thickness extending along said end portions to stiffen the same and to hold the sponge in mopping position.

3

2. A mop as defined in claim 1 wherein the said studs and said backing plates are integral.
